UNITED STATES PATENT OFFICE.

JACOB SKYDEL, OF NEW YORK, N. Y.

NIPPLE FOR NURSING-BOTTLES.

1,170,354.

Specification of Letters Patent.

Patented Feb. 1, 1916.

Application filed October 18, 1913. Serial No. 795,994.

To all whom it may concern:

Be it known that I, JACOB SKYDEL, a citizen of the United States, residing at New York city, in the county of New York and State of New York, have invented certain new and useful Improvements in Nipples for Nursing-Bottles, of which the following is a specification.

This invention relates to nursing bottles for infants, and particularly to certain useful improvements in nipples therefor.

The invention contemplates the production of an inexpensive and satisfactory device of this class consisting of a nipple, having among its objects the filtration of the liquid drawn therethrough, means whereby the nipple is readily adjusted upon the neck of the bottle, and finally an inelastic, sanitary and efficient device which can be manufactured and placed upon the market at a minimum cost.

The above and additional objects are accomplished by such means as are illustrated in their preferred embodiment in the accompanying drawings, described in the following specification and then more particularly pointed out in the claims which are appended hereto and form a part of this application.

30 In describing my invention in detail reference will be had to the accompanying drawings wherein like characters denote like or corresponding parts throughout the several views, and in which:—

35 Figure 1 is an elevation illustrating the application of the invention; Fig. 2 is a longitudinal sectional view of the device as is illustrated in Fig. 1; and Fig. 3 is a section on the line 3—3 of Fig. 2.

40 Referring now to the drawings wherein is illustrated the preferred embodiment of my invention the numeral 1 designates a bottle or receptacle for infant's food, preferably made of glass or other vitreous material, to the neck of which a nipple designated as an entirety by the numeral 2 is attached.

45 The nipple in its preferred form is composed of some such non-elastic material as celluloid, and comprises the usual neck 3, body 4 and head 5, the latter having an outlet aperture or opening 6 formed therein through which the liquid is adapted to pass. At the base of the body 4 of the nipple, a shoulder 7 is formed, annular in shape, and disposed for engagement with the upper ex-

tremity of the bottle 1. A constricted base 8 is formed in axial alinement with the nipple 2, the said base adapted to fit or extend into the neck of the bottle 1 and to 60 be embraced at a point adjacent the shoulder 7, by a suitable band 9, preferably of cork, the latter being disposed for engagement with the inner wall of the bottle neck to provide a securing means for the nipple 65 as well as providing a means whereby the dispensation of the liquid contents cannot be effected other than through the opening 6 aforesaid. The constricted base 8 is exteriorly threaded as at 10 throughout a portion of its length over which the interiorly threaded annular extension 11 of a semi-spherical perforated base 12 is arranged, the latter providing for the filtration of the liquid drawn from the bottle. 70

75 The above being substantially a description of my invention, its use and operation are as follows:—The perforated base having been threaded or attached to the constricted base 8 of the nipple, and the cork band 9 80 arranged to embrace the said constricted base at a point above the threaded portion thereof, it is apparent that the nipple may then be attached to the bottle 1 in connection with which it is used. By forcing the 85 said constricted base within the bottle neck, (the cork band firmly engaging the inner wall of the bottle) until the shoulder 7 firmly engages the bottle top, a closure for the bottle is provided to prevent the escape 90 of the liquid contents other than through the opening 6 in the nipple head.

95 From the above, taken in connection with the accompanying drawings it is still further apparent that a sanitary and highly efficient nipple is provided; that the peculiar formation of the filter 12 is such as to render the cleaning thereof facilitated; and that by reason of the band 9 and shoulder 7, both being forced into firm engagement 100 with the bottle neck, a tight closure is effected for the bottle, the said band also providing an attaching or securing means for the nipple 2, whereby the same is maintained in operative relation with the bottle 105 1 until forcibly withdrawn from engagement therewith.

110 It will be understood that the above description and accompanying drawings comprehend only the general and preferred embodiment of my invention, and that various minor changes in details of construction,

proportion and arrangement of parts may be made within the scope of the appended claims and without sacrificing any of the advantages of my invention.

5 Having thus fully described my invention, what, I claim as new and desire to secure by Letters Patent, is:—

1. A nipple for nursing bottles including a body portion, a base portion, a detachable semi-spherical filter carried by the said base portion, the said filter and the said base both fitting within the neck of the bottle, and means carried by the said base adapted to engage the bottle neck to provide a fastening means for the nipple.
- 15 2. A nipple for nursing bottles including a body portion, a constricted base depending from and formed integrally with the

said body, the said base forming an annular shoulder at the base of the said body, a semi-spherical filter detachably carried by the said base, the said base and the said filter both fitting within the neck of the bottle, and a band arranged to embrace the said base above the said filter, said band and said shoulder being adapted to engage the neck of the bottle to provide for the fastening of the nipple to the bottle as well as a closure therefor.

20 25 30 In testimony whereof I affix my signature in presence of two witnesses.

JACOB SKYDEL.
